UNITED STATES PATENT OFFICE.

CARLETON ELLIS, OF MONTCLAIR, NEW JERSEY.

LAVAGE PROCESS AND PRODUCT THEREFOR.

No Drawing.

Application filed January 19, 1928. Serial No. 248,016.

This invention relates to a method of de-greasing and cleansing the scalp and relates particularly to a method involving the employment of a vehicle of oil-dissolving or dislodging strength, and to products utilizable in such methods.

In the practice of the invention in the preferred form a nearly anhydrous vehicle capable of dissolving both oily and aqueous exudations of the skin may be employed.

By the employment of a vehicle possessing these dual properties I am able to secure results in the treatment or cleansing of the scalp which cannot be effectively obtained by means heretofore used.

Such a vehicle I have discovered is procurable from the olefines of cracked petroleum by sulphation and hydrolysis, followed by rectification and concentration to yield an anhydrous, or nearly anhydrous mixture of isopropanol and tertiary butanol. The method of derivation does not form a part of the present invention, which relates to the employment of such a vehicle as a cleansing or lavage agent for the hair and scalp. I regard, however, such derivation as meritorious for various reasons, one being that the preferred components of the vehicle, not long ago merely chemical rarities are now cheaply and abundantly available from petroleum; another reason is that a product of this derivation may contain traces of bodies such as sulphur compounds which have certain attributes of therapeutic value.

Before discussing my invention in its more specific and detailed aspects, I wish to call attention to the ever present problem of hair cleansing and to explain why methods in use have not been satisfactory.

The most widely prevailing form of scalp disease producing irritation and dandruff is, in my opinion, a form of eczema known as seborrhea. Washing the scalp with soap and water tends to increase this irritation and weaken the hair follicles. Benzine or gasoline are not solvents for aqueous secretions, cause a sensation of burning of the scalp if the latter is rubbed during application and involve an undue fire hazard. Rubbing the dry scalp with orris root and the like is ineffectual. Various other substances have secondary effects which are not salutary.

I have discovered that concentrated isopropanol, particularly with some tertiary bu-

tanol, not only is an almost universal solvent for the various oily and aqueous exudates the skin (scalp), but that in constant and frequent use as a "dry cleaner" for the scalp, undesirable secondary effects do not arise. Instead, by freeing the scalp of its burden of self-irritating secretions, the vehicle of the present invention exerts curative properties with respect to seborrhea which are very striking and which are very important in the treatment of so obstinate a condition of the scalp as seborrhea brings in the course of time.

The employment of this vehicle as a dry cleaner for the scalp was so wide a departure from anything known in the prior art that its use was strongly discouraged due to the unknown possibilities of such material.

One manner of using this cleaner was as follows:

Concentrated isopropanol containing a few per cent of tertiary butanol, the mixture being of oil-dissolving strength (in this case 98-99 per cent was poured on the scalp daily in lavage proportions to thoroughly drench both hair and scalp without using substantially any more than sufficient for a thorough wetting. The hair was promptly dried with an absorbent medium, e. g., a cloth. The exudations of the scalp thus were largely transferred to the cloth. Dandruff scale was loosened by the treatment and could be readily brushed out. In one case after using in this way daily for several days, a seborrheal condition which was not checked by any other means, completely subsided and the scalp became perfectly clean and free from scale.

After the expiration of several months daily use of the vehicle in this manner in a limited way without any signs of unfavorable secondary effects, but on the contrary with complete freedom from seborrhea and dandruff, it was tried by others with results which were immediately successful. Tests on a more extensive scale were inaugurated, and at the present time a considerable number of persons are using this vehicle regularly. Very favorable reports on these cases have been received, with no report of unfavorable secondary effects. Tests for more than two years have shown conclusively that the vehicle does not cause undesirable secondary effects.

The vehicle has also been examined with

- reference to the possibility of igniting it by a spark produced by so-called frictional electricity. In dry cold winter weather when movement about a carpeted room creates a charge of electricity in a person, discharging on any conductor in proximity, thin layers of the vehicle have been placed in metal pans which have been grounded. Thereupon a person has moved about the room briskly to obtain a charge which was discharged as a spark through the thin layer of the vehicle. Repeated discharging of the largest sparks which could thus be produced, was attempted without ever being able to ignite the vehicle.
- 15 I consider therefore that the vehicle especially when containing a small percentage of water (say 1 to 3 per cent) not sufficient to destroy the oil and grease dissolving powers of the medium is not hazardous to use because 20 of sparks generated as aforesaid. I am the more confident of this because sparks frequently discharged from the tips of fingers when they were dripping wet with the vehicle has never resulted in ignition.
- 25 The operation of treating the hair should, however, be conducted away from an open flame.

Instead of wetting the hair and immediately wiping dry, the operation may be 30 modified by applying a considerable excess of the vehicle and allowing the excess to flow off into a receptacle.

The vapors of the vehicle being penetrating, it is desirable in some cases to permit of 35 somewhat longer contact with the scalp. This may be accomplished by wetting the hair and scalp thoroughly with the vehicle and winding a towel about the scalp, keeping in this position for several minutes until the liquid 40 and vapor has penetrated the pores in a most complete manner.

One great advantage to users who have 45 artificial waves in the hair is that the scalp may be fully cleansed without destroying such waves. The hair may be cleansed on short notice in the space of a few moments without that complete annihilation of the coiffure which results from the more lengthy procedure with soap and water. This is of very 50 great advantage to women who have only a limited time to conclude a toilette.

Treatment of oily scalp is especially effective as undue oiliness is frequently accompanied by seborrhea. There is also a dry 55 stage of seborrhea when the oil glands cease to function and I have observed that "dry scalp" due to this cause has been stimulated to normality by frequent use of the vehicle. Thus, instead of being "drying" as might be 60 expected, it was a surprise to find the vehicle to cause a flow of oil in dry seborrhea.

When circumstances appear to indicate such a procedure, the vehicle may contain a small proportion of mineral or vegetable oil,

glycerine and the like, not sufficient in 65 amount to impair the proper operation of said vehicle. Also medicating agents such as resorcin, beta naphthol, quinine, and the like, may be added in some cases.

The vehicle, however, has of itself a "tonic" 70 effect and being volatile, leaves the scalp without a deposit of a powerful chemical substance such as is used in some hair tonics on the market.

I am very dubious about the desirability 75 of keeping the scalp impregnated with the mercury dichloride, certain phenolic bodies and other powerful non-volatile substances found in hair tonics used in some treatments. The scalp absorbs such substances readily and 80 this absorption going on week after week may have a cumulative effect in impairing some vital organ.

Hence it is a source of satisfaction to me to have found a completely volatile material 85 which has the requisite stimulating effect, presumably by subtraction (extraction) rather than by addition. The stimulus apparently is very simply secured by relieving the pores of the scalp of their burden of 90 exudations. While I have set forth particularly the low boiling alcohols derived from the olefines of cracked petroleum, I do not limit myself in the broader aspects 95 of the invention to the illustrative compositions. Nor do I preclude the addition to such compositions of various volatile liquids which may be used in conjunction with the foregoing to carry out the process of cleansing the 100 hair and scalp. The addition of ethyl alcohol, volatile chlorinated bodies such as carbon tetrachloride, tri-chlorethylene, and the like, is not precluded.

Preferably, as indicated, the process involves treating the hair and scalp by applying 105 freely thereto a laving quantity of a nearly anhydrous vehicle comprising isopropanol preferably carrying from 2 per cent to 10 per cent of tertiary butanol and 1 per cent to 3 per cent of water.

What I claim is:—

1. The process of treating hair and scalp which comprises applying thereto at least a saturating quantity of a nearly anhydrous mixture of isopropanol and a minor proportion of tertiary butanol, said mixture being of oil-dissolving strength, and drying the scalp with an absorbent medium; whereby a substantial portion of the excretions of the 115 scalp are transferred to said medium.

2. In the process of treating hair and scalp, the step which comprises applying freely thereto a laving quantity of a nearly anhydrous cleansing agent comprising isopropanol.

3. In the process of cleansing hair and scalp the step which comprises applying thereto a laving quantity of a vehicle of oil-

dislodging strength comprising isopropanol. tion, and absorbing the vehicle and dissolved 10

4. In the process of cleansing hair and scalp matter on fibrous tissue.

the step which comprises applying thereto a laving quantity of a cleansing agent com-

5 prising isopropanol.

5. The hair cleansing process which com- prises wetting the hair freely with a volatile vehicle comprising isopropanol and tertiary butanol, the latter present in minor propor-

6. A hair and scalp cleanser comprising a cleansing agent containing isopropanol.

7. A hair and scalp cleanser comprising a cleansing agent containing isopropanol and 15 a minor proportion of tertiary butanol.

CARLETON ELLIS.
